[57] CLAIM

The ornamental design for a food processor, as shown and described.

DESCRIPTION

FIG. 1 is a top and left side perspective view of a food processor, showing my new design;

FIG. 2 is a left side elevational view thereof, the right side being substantially a mirror image thereof omitting the selector switch shown in the lower portion of FIG. 2;

FIG. 3 is a front elevational view thereof;

FIG. 4 is a rear elevational view thereof;

FIG. 5 is a top plan view thereof; and

FIG. 6 is a bottom plan view thereof.

The elevational view of the side of the food processor of the invention opposite that shown in FIG. 2 is a mirror image of the view shown in FIG. 2 except that the side not illustrated does not include the selector switch shown in the lower portion of the FIG. 2 view.
